UNITED STATES PATENT OFFICE.

CHARLES E. FOULKS, OF COVINGTON, KENTUCKY.

RACE-TRACK BARRIER.

SPECIFICATION forming part of Letters Patent No. 754,986, dated March 22, 1904.

Application filed April 27, 1903. Serial No. 154,428. (No model.)

To all whom it may concern:

Be it known that I, CHARLES E. FOULKS, a citizen of the United States, residing at Covington, in the county of Kenton and State of Kentucky, have invented certain new and useful Improvements in Race-Track Barriers; and I do hereby declare the following to be a full, clear, and exact description of the invention, such as will enable others skilled in the art to which it appertains to make and use the same.

My invention relates to barriers or starting devices for race-tracks. One of its objects is to provide a barrier having an improved movement whereby it moves in the desired direction and very rapidly.

Another object is to provide improved means for setting up and taking down or re-moving the barrier, enabling it to be quickly moved and set up at different parts of the track.

Another object is to provide means for automatically unshipping the barrier without injury thereto or to the horses in case it is ridden down.

Another object is to provide improved means for releasing the catch at one side by the operation of the lever at the opposite side.

Another object is to automatically sound the gong when the barrier is released.

It further consists in certain details of form, combination, and arrangement, all of which will be more fully set forth in the description of the accompanying drawings, in which—

Figure 1 is a perspective view of my improved mechanism in position for use. Fig. 2 is a detail, partly in section, of the releasing mechanism. Fig. 3 is a detail, partly in section, of the automatic unshipping mechanism. Fig. 4 is an enlarged section on line *v v* of Fig. 1.

The mechanism herein shown is to be employed in starting the horses, so that they will all pass the starting-line simultaneously. In practice the barrier would be set up at the desired point across the track and the horses driven or ridden abreast of each other toward the barrier. If they are in proper alinement

when close to the barrier, the lever is tripped to move the barrier out of the way of the 50 horses, and the race commences; otherwise the horses are returned for a fresh start.

A A' represent posts or supports upon which the mechanism is mounted and which are preferably permanently located at opposite sides 55 of the track. The frames B B' are secured in position upon the posts in any suitable manner, being preferably provided with sockets fitting the tops of the posts and set-screws or other means for clamping them in position 60 thereon. The upper ends of these frames are provided with short horizontal studs C C', upon which are journaled the collars D D'. These collars have the stop-lugs E E' projecting from one side and the spring-arms F F' 65 from the other side.

G represents the barrier, consisting of a stout tape or ribbon, the opposite ends of which are attached by rings to the free ends of the spring-arms.

H H' represent springs coiled on the studs C C', one end of the springs being rigidly attached to the ends of the studs by means of collars I I' and the other end engaging the collars D D' in such manner that the tension 75 of the springs tends to normally hold them with the spring-arms F F' raised above the collars D D', in which position the lugs E E' engage the buffers or stops J J', which are preferably cushioned with rubber to prevent 80 noise and injury to the parts.

In order to set the barrier in position for use, the arms F F' are brought down by hand, the free end of bar F is passed into the entrance of the L-shaped slot K, and the free end 85 of arm F' is pressed or sprung into the slot K', where it is held by a spring-latch M. The springing of the free end of arm F' by reason of the connecting-barrier springs the arm F, drawing its free end toward the frame B' and 90 into the end of the L-shaped slot K, thereby locking it in place until the arm F' is released by the latch, when it springs back and frees itself from the slot K and is quickly thrown to a position above the collar D. The arm F' 95 also at the same time springs clear of the slot

K' and assumes a similar position above the collar D', carrying the barrier in a semicircular path, as indicated in dotted line, out of the way of the horses, which pass under the barrier. The arms F F' are sufficiently light so that their free ends can be sprung out of their normal position to enter the slots K K', and in order to increase their tendency to spring I preferably provide loops in said arms 5 between their free ends and the studs C C'. The latch M is beveled on one face, so as to be forced back by pressing the end of arm F' into the slot K'. N represents a spring, seated in a cup O, for holding the latch normally in 10 the raised position. P represents a lever for depressing the latch to release the arms F F' and the barrier. This lever is pivoted at p, and its under face is engaged by the upper curved face of the collar p', attached to the 15 latch, so that when the free end of the lever is pressed down the collar compresses the spring N and the latch is depressed.

In order that the barrier may not be broken or other parts of the device strained or broken 20 should the horses strike the barrier, I provide means for automatically unshipping or releasing the barrier from either one or both of the arms F F', which preferably consists of the hook Q, having a keeper R, held in place by 25 a spring R', so that when any undue strain is applied to the barrier the keeper is withdrawn, allowing the ring r at the end of the barrier to slip off the hook Q to automatically release the barrier instead of breaking it. In Fig. 1 30 I have shown the automatic release applied at one end only of the barrier; but it may be applied at both ends, if desired.

In order that the gong may be sounded simultaneously with the release of the barrier, 35 I mount the gong T on one of the frames B in such manner that the movements of the barrier will impart motion to the gong-lever to sound the gong. This is preferably effected by providing one or more lugs t on the collar D, which as the collar turns will contact with the gong-lever u to sound the gong.

It will be noted that by providing posts A A' at various points along the track the operative parts can quickly and readily be removed from one set of posts to another, as required for short or long races; also, that the mechanism is strong, simple, and reliable in action and that the direction of travel of the barrier is that best suited to quickly and 50 effectively remove the barrier from the path of the horses. The mechanism here shown is capable of considerable modification without departing from the principle of my invention.

Having described my invention, what I claim is—

1. In a barrier, the opposite supporting-frames, the elastic or spring arms pivoted at one end, and adapted to be sprung at their free ends laterally out of their normal path 60 of travel, and to return thereto when released, means for locking said arms in said lateral position, and mechanism for turning said arms on their pivots when released to lift the barrier out of the way of the horses, whereby the elasticity of the arms assists to free them when the latch is tripped.

2. In a barrier, the opposite supporting-frames, the pivoted spring-arms adapted to be sprung at their free ends out of their normal 70 path of travel, and to return thereto when released, means for turning said arms on their pivots when released to elevate the barrier, mechanism for locking the free ends of said arms with their free ends downward by springing them out of their normal position, so that the elasticity or spring of the arms between their pivots and their free ends insures their release when the latch is tripped.

3. In a barrier, the opposite supporting- 80 frames, the pivoted arms, a barrier attached at opposite ends to the free ends of said arms, a recess and latch to receive and lock one of said arms in the lower position, a recess to receive the free end of the other arm, said arm being 90 locked therein by the strain exerted by the barrier, and adapted to be automatically released when the latch releases the strain on the barrier.

4. In a barrier the opposite supporting- 95 frames, the arms pivoted thereto, a barrier connected to the free ends of said arms, a latch adapted to lock one of said arms in the lower position, and means operated by the strain of the barrier for locking the other arm in the 100 lower position, so that when the latch is released both arms are released.

5. In a barrier, the upright posts, the detachable supporting-frames mounted thereon, the pivoted spring-arms, means for throwing 105 said arms to the raised position when released, a barrier connected to the free ends of said arms, a latch adapted to lock one of said arms in the lower position, and means operated by the strain of the barrier for locking the other 110 arm in the lower position, so that when the latch is released both arms are released.

In testimony whereof I have affixed my signature in presence of two witnesses.

CHARLES E. FOULKS.
